UNITED STATES PATENT OFFICE.

CHARLES K. BENNETT, OF EAST CLEVELAND, OHIO, ASSIGNOR TO THE ECLIPSE MUSICAL COMPANY, OF CLEVELAND, OHIO, A CORPORATION OF OHIO.

DISPLAY-FIXTURE.

1,371,464.

Specification of Letters Patent. Patented Mar. 15, 1921.

Application filed December 23, 1918. Serial No. 267,942.

To all whom it may concern:

Be it known that I, CHARLES K. BENNETT, a citizen of the United States, and a resident of East Cleveland, county of Cuyahoga, and State of Ohio, have invented a new and useful Improvement in Display-Fixtures, of which the following is a specification, the principle of the invention being herein explained and the best mode in which I have 10 contemplated applying that principle, so as to distinguish it from other inventions.

The present improvements, relating, as indicated, to display fixtures, have regard more particularly to fixtures for displaying 15 phonograph records of the flat or disk type. The difficulty of bringing such records to the attention of prospective customers, and of assisting them in making a selection where only a catalogue list is available, has long 20 been understood by salesmen in this field. The object of the present invention, accordingly, is to provide a device whereby records (and other similar articles, there being no 25 intention to limit the utilization of the invention to the field indicated) may be displayed in readily accessible form, without taking up much space or subjecting the records to damage through unnecessary handling.

To the accomplishment of the foregoing and related ends, the invention, then, consists of the means hereinafter fully described and particularly pointed out in the claim, the annexed drawing and the following 30 description setting forth in detail certain mechanism embodying the invention, such disclosed means constituting, however, but several of the various mechanical forms in which the principle of the invention may be 40 used.

In said annexed drawing:—

Figure 1 is a front elevation of one unit of my improved display device; Fig. 2 is a section thereof taken on the line 2—2, Fig. 45 1; Fig. 3 is an elevation similar to that of Fig. 1, but illustrating a modified (and preferred) construction of the same; Fig. 4 is a section of such modified construction, taken on the plane indicated by the line 50 4—4, Fig. 3; and Fig. 5 is a perspective view of a rack carrying a number of such units.

The base of the device, in the case of either constructional form thus illustrated, consists of a back member comprising a flat relatively rigid sheet 1, preferably of cardboard

having a width somewhat greater than that of the records, or other articles, it is desired to display, and of a length or rather height sufficient to permit the display of the desired number of such records. For receiving and holding the individual records, a series of pockets is provided on one or both faces of such back member. In the constructional form illustrated in Figs. 1 and 2, these pockets consist of separate envelops 2, the 60 fronts 3 of which are lower than the backs 4, so that something more than the upper half of the record will be exposed to view when placed therein. Preferably such fronts will be cut in the form of a broad V, the 65 lower corner of which will clear the label of the record so as to leave such label entirely exposed to view. The back of each envelop overlies the front of the one next above, being glued or otherwise firmly attached thereto, and such envelops are similarly firmly attached by means of glue or equivalent means (e. g. by being sewn) onto the back member. Staples may also be used for this purpose. 70

The modified construction illustrated in Figs. 3 and 4 is designed to facilitate production of the device on a commercial scale, and at the same time it presents some additional operative advantages. In place of a series 85 of envelops secured in the fashion just described to the back member, I here utilize a sheet 5 of stiff paper, or equivalent material, of approximately the same size as the back, such sheet being cut at spaced intervals by broad V-shaped slits 6 corresponding in outline with the fronts of the aforesaid envelops. The sheet is then firmly secured about its edges to the back by means such as previously described for securing the 90 envelops thereto, and the depending angular flaps 7 corresponding with the successive slits are similarly attached to such back. In the case of such flaps, however, I preferably use two tacks or ordinary paper fasteners 8 100 spaced transversely of the sheet equal distances from the median line thereof, the result being that when a record is inserted through the slit above such fastening devices, it will not only be supported at the 105 proper height in the pocket that is thus in effect formed, but will be nicely centered as well. It will be understood that the same pocket may be arranged to receive a larger or smaller record by locating the fastening de- 110

vices 8 just mentioned the proper distance below the corresponding slit.

- In the case of the construction under consideration, either one or both sides of the board may be equipped to receive records just as before. I also preferably bind the edges of the sheet or sheets and the base or back board together, using a strip 9 of either cloth or metal as preferred. Where of metal such strip obviously provides a rectangular frame having side and bottom members formed with inwardly facing channels, within which the edges of the sheet or sheets and of the back board are confined as shown in Fig. 4.
- 10 A sheet when slit in the fashion last described, or the series of envelopes arranged as in the first described construction may be regarded as a series of transverse relatively narrow strips of material extending transversely of the back board having their lateral edges attached to the corresponding sides of said board and being secured along their lower edges to said board intermediate of the sides of the same.
- 15 The device, in either of the two forms described, constitutes a unit which may be used by itself by being suspended against a wall, or supported on an easel, or a number of such units may be mounted in any one of
- 20 the several familiar types of swinging display racks, as illustrated in Fig. 5. By using such a display rack, a large number of records may obviously be stored in a very small space, and yet by simply turning the
- 25 30 35 several leaves over, any one interested in examining the records may scan their titles and quickly select and abstract any one in the collection. The record need not be handled at all unless it is desired to withdraw

the same, and the danger of damage is thus reduced over present methods of displaying and handling records. A device of this sort lends itself readily to the display of special selections of records which may be classified and placed in separate series of holders and in a variety of other ways lends itself to the merchandising of articles of the class in hand.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

In a device for exhibiting phonograph record tablets having titles printed at their centers, the combination of a flat central member, a supporting frame formed of a channeled strip surrounding said member, a vertical series of relatively narrow transversely extending pocket-forming sheets secured to each side of said central member, 60 each sheet having its upper edge cut away for display purposes and having its lateral edges confined within the channels of the side members of the frame, and a pair of combined sheet-attaching and tablet-positioning elements connecting each of said sheets to said central member at points centrally of the respective half-portions of said sheets.

Signed by me, this 21st day of December, 75 1918.

CHARLES K. BENNETT.
